EJECTOR MECHANISM FOR METAL FORMING PRESSES

Henry A. Zwierlein, Euclid, Ohio, assignor to The Ajax Manufacturing Company, Cleveland, Ohio, a corporation of Ohio

Application December 3, 1938, Serial No. 243,836

11 Claims. (Cl. 78—39)

This invention relates to a new and improved ejector for forging presses, and particularly to an ejector for forging presses utilizing a crank operated ram.

In forging operations on presses of the character above mentioned, the heated metal work piece is pressed into contact with the walls of the die cavities so intimately that a large amount of heat in the work piece passes into the dies sufficiently rapidly so that the dies frequently are damaged by such heat. It is desirable, and often necessary, therefore, to eject the formed work piece completely from the die as promptly as possible, or at least to partially eject the work and thereby reduce the area and tightness of contact between the work piece and the walls of the die cavity.

The principal objects of the present invention are to provide, in a forging press, means for more quickly ejecting formed articles from the dies; to provide an ejector which operates to initiate ejection of the formed work piece from the dies immediately upon the beginning of the movement of the ram on its return stroke, and to eject the work piece entirely from the die cavities as soon as the dies are separated a sufficient distance to permit completion of the ejecting operation.

A more specific object is to provide, in a press having a pitman driven ram, an ejector which is operated on its ejection stroke by cooperation of means on the frame and on the ram during the initial part of the ejecting operation, and by the cooperation of means on the ram and on the pitman during the remainder of the ejecting operation, the operations of the ejector by these means being so related that the second means becomes fully operative in a delayed relation to the first means, and the first means becomes inoperative after the second means is fully operative.

A correlative object is to provide a latch means on the frame, and a cooperating member carried by the ram and which is engaged with the latch and thereby becomes effective for moving the ejector on its ejecting stroke during initial movement of the ram on its return stroke, and a crank operated means on the ram arranged to cooperate with said member for completing the movement of the ejector on its ejecting stroke and for relieving the latch of any frictional and other stresses preparatory to moving the latch out of engagement.

Other objects and advantages will become apparent from the following specification, wherein reference is made to the drawings, in which:

Fig. 1 is a front elevation of a forging press embodying the principles of the present invention;

Fig. 2 is a fragmentary cross sectional view taken on a plane indicated by the line 2—2 in Fig. 1; and

Fig. 3 is a top plan view of the structure illustrated in Fig. 1.

Referring to the drawings, the forging press shown for purposes of illustration is of the upright type and comprises a frame 1 having laterally spaced upright columns 2. The upright columns terminate at their lower end in a base portion 3, the upper surface of which is beveled and supports a die adjusting wedge block 4. An anvil 5 is supported on the block 4 and, in turn, supports a lower forging die 6. Adjustment of the height of the die 6 is effected by movement of the wedge block 4 forwardly and rearwardly of the frame to the desired position.

The upright columns 2 carry vertical guides 7 between which a ram 8 is mounted and guided for reciprocating movement vertically. The ram 8 is operated by a pitman 9 which is pivotally connected at its lower end to the ram by a suitable wrist pin 10 and extends upwardly therefrom. The upper end of the pitman is connected to a suitable eccentric 11 on a driven shaft 12 which may be driven by any suitable power means (not shown).

In the under face of the ram is fitted a bearing plate 13 against which is supported and buttressed an anvil 14 against which, in turn, is carried an upper die 15. In the illustrative example, the dies 6 and 15 are closed and the forging operation is completed so that a forged work piece, such as indicated at 16, is ready for removal from the die cavities. For ejecting the work piece 16 from the cavity of the upper die 15, a suitable ejector is provided, the ejector comprising a lower pin 17 having an enlarged diameter collar portion 17a at its upper end, and a separate, cooperating pin 18 thereabove. In the ram 8 is a vertical passage 19 which is aligned with a larger passage 20 in the anvil 14. The passage 20, in turn, is aligned with a passage 21 of the die 15 which opens into the cavity. These passages accommodate the pins 17 and 18, the collar portion 17a cooperating with the shoulder between the passages 20 and 21 for limiting the downward movement of the pins 17 and 18 and preventing them from falling out of position when the dies are separated and the work piece is removed. A passage 22 is provided in the ram and, in the form illustrated, extends for

wardly and rearwardly thereof and is open at both ends and intersects the passage 19. The upper end of the ejector 17 extends into the passage 22.

5 Carried by the ram is an ejector operating lever 23. The lever 23 is accommodated in the passage 22 and preferably extends entirely therethrough. At its rear end, the lever 23 is mounted on the ram 8 for swinging or rocking movement 10 in a vertical plane in the passage 22 about a fulcrum which is preferably fixed, or substantially so, with respect to the ram. In the form illustrated, this fulcrum comprises a pivot pin 24 fixedly mounted in suitable flange portions 25 15 of the ram.

The forward end of the lever 23 extends outwardly beyond the front of the ram 8 and into a position to be engaged by lever actuating means which are mounted on the frame 1 of the 20 press in a fixed position vertically.

The lever actuating means is preferably in the form of a latch comprising a rigid latch element 26 which is connected by a pivot pin 27 to the frame 1, so as to swing forwardly and rearwardly of the frame in a vertical plane. The latch element 26 is urged to swing about its pivotal axis and toward the ram or rearwardly of the frame 1 by means of a suitable return spring 28. The spring 28 is operatively interposed between an abutment on the frame and a suitable abutment on an eye bolt 29 which is connected to a crank arm 30 of the latch element 26. The latch element has a latching abutment 31 which, when the element 26 is moved to its rearward position by the spring 28, lies in the path of movement of the outer end 32 of the lever 23 so as to engage and constrain the outer end of the lever from ascending with the ram. The abutments 31 and 32 are so positioned that they 35 engage when the ram 8 is at the end of its working stroke and ready to start its return stroke.

The lever 23 has an abutment 33 which engages a complementary abutment 34 of the ram 8. The 45 abutments 33 and 34, when in contact, permit the ejector pins 17 and 18 to move to a fully retracted position in which position the collar 17a is in engagement with and is firmly buttressed by the bearing plate 13 for withstanding the load during the forming operation.

50 A suitable return spring 35 is mounted on a rod 36 which engages the lever 23 rearwardly from the pivot pin 24, the spring 35 being operatively interposed between a suitable abutment on the ram and an abutment on the rod 36. The spring 55 acts to urge the lever to the position illustrated in Fig. 2, wherein the abutments 33 and 34 are in contact.

With the structure thus far described, it is apparent that as the ram ascends, the pivot 24 60 rises concurrently therewith, as also does the rear end of the lever 23. However, due to the cooperation of the abutment 31 of the latch element 26 and the abutment 32 of the forward end 65 of the lever, the forward end of the lever cannot rise with the ram. Instead, the lever swings or rocks about the abutment 31 as a fulcrum. As a result, the central or ejector engaging portion of the lever 23, though rising with respect to the frame 1, moves downwardly with respect to the ram a distance equal to about one-half of the upward movement of the ram, thus depressing the ejector on its ejecting stroke relative to the ram at a rate equal to about one-half the rate 70 of ascension of the ram 8 in the illustrative ex-

ample. Consequently, the ejector rises relative to the die 6, but lowers relative to the die 15, thereby ejecting the formed work piece from the die 15 while permitting the article concurrently to be ejected from the die 6. The desired relative 5 travel of the ejector and dies 6 is determined to meet the conditions of use of the particular forging press. By changing the location either of the pivot 24 or abutments 31 and 32, corresponding changes being made in the length of the lever 10 23, the ejector is positioned either nearer to or farther from the pivot 24 than in the illustrative example, thus either decreasing or increasing the travel of the ejector relative to the dies.

As the ram continues to rise, the lever 23 is 15 constrained by the latch element 26 but it is necessary, if the ram is to continue rising after the lever 23 has reached a predetermined ejecting position, to release the latch element 26 from the lever 23. For this purpose, a cam 37 is provided on the latch element 26, and a corresponding cam 38 is provided on the ram, these cams cooperating to move the latch forwardly of the frame, thereby to displace the abutment 31 from the path of the abutment 32 when the ram rises 25 a predetermined distance on its return stroke.

As the ram descends on a subsequent stroke, the latch element 26 is permitted to be swung inwardly by the spring 28 until it engages the forward face of the lever 23, as soon as the cam 38 30 moves downwardly away from the cam 37. When the ram is lowered sufficiently, the forward face of the lever 23 moves to a position below the abutment 31, whereupon the latch element is swung into position to re-latch the forward end 35 of the lever 26 and constrain it from upward movement preparatory to the repetition of the cycle. It is apparent that the operation of the ejector by the latch mechanism and lever 23 initiates the ejecting operation of the ejector immediately upon the beginning of movement of the 40 ram on its return stroke.

After the ram is moved a predetermined distance upwardly on its return stroke, it is often desirable to effect movement of the ejector on its 45 ejecting stroke with greater rapidity than would be effected by the cooperation of the latch element 26 and the lever 23. For this purpose, an additional means is provided for operating the lever. This additional means comprises a pin 40 slidably mounted in a suitable bore 41 extending 50 from the passage 22 to an upwardly exposed face portion of the ram. The upper end of the pin 40 extends beyond the upper face portion and into a position to be engaged by an operating abutment 42 on the pitman 9.

When the ram starts on its return stroke, the abutment 42, due to the rocking action of the pitman, approaches the upper end of the pin 40 55 but does not strike the pin until there has been a substantial upward movement of the ram. The rate of approach of the abutment 42 toward the upper end of the pin accelerates as the ram rises and finally engages the pin and forces it downwardly with respect to the ram. The pin 40 engages the lever 23 at a portion which is nearer to 60 the pivot pin 24 than the portion of the lever 23 which is engaged by the latch 26. Consequently, a more rapid movement relatively downwardly 65 with respect to the ram is imparted to the lever 23 by the pin 40 after the ram has been moved a predetermined distance on its return stroke. In this manner, the initial operation of the ejector is effected by the latch 26 while the remainder 70 of the ejecting action is effected by the pin 40 75

and the cooperating abutment 42 of the pitman 9.

In operation, for example, in a press of the general proportions illustrated, the extent of movement of the ejector pin first by the latch 5 and then by the pin 40 is such that any movement of the pin 17 by the latch element 26 and lever 23 for a given ram movement is substantially one-half of the ram movement and is effective during the first 25° of movement of the shaft 12.

10 When the crank reaches about 25° from the down position of the ram, the pin 40 and latch 26 are operating concurrently to move the ejector pin 17 the same distance. Until this time, no movement of the ejector pin 17 has been effected by the pin

15 40. However, after the pitman has been moved another 5° on the return stroke of the ram, the pin 40 is moving the ejector 17 on its ejecting stroke and the latch element 26 is ineffective. The movement of the ejector by the pin 40 may be 20 more rapid than that effected by the latch element 26.

At this point, an important feature should be noted. During the upward or return movement of the ram 8, the latch element 26 remains effective until the pin 40 becomes effective, and since thereafter the pin 40 moves the lever 23 a greater distance downwardly relative to the ram than it would be moved by the latch, the abutment 31 of the latch element 26 is lowered out of engagement 30 with the abutment 32 of the lever 23. Thus, by the time the cams 37 and 38 become effective, the latch is freed from all operating and frictional stresses with obvious advantages including reduction of wear on the abutments 31 and 32 and the 35 cam surfaces 37 and 38.

An ejector for the die 16 is provided also and comprises an ejecting pin 50 operated by a suitable bar which in turn is operated by a cam (not shown). The bar 51 is moved by its operating 40 cam, which may be driven in timed relation to the shaft 12 of the press, in a manner such that the pin 50 rises a short distance, for example, approximately one-eighth of an inch in the illustrative example, during the initial part of the idle 45 or return stroke of the ram and remains in that position until the top die has receded sufficiently far to permit ejecting the piece entirely out of the dies.

Thus, immediately upon travel of the ram on its 50 return stroke, the work piece is moved partially out of the upper die 15, and very early during the return stroke of the ram, the piece 16 is likewise moved partially out of the bottom die so that the area and period of contact between the work 55 piece and the dies 15 and 16 is reduced to a negligible amount, and promptly thereafter the piece is freed entirely from both dies.

Having thus described my invention, I claim:

1. In a forging press including a frame, a 60 reciprocable ram, means for driving the ram, a die carried by the ram, and an ejector for work formed by the die carried by the ram; means for operating the ejector and comprising ejector operating means carried by the ram and movable concurrently therewith and relative thereto, and operative, when moved in one direction relative to the ram, to operate the ejector on its ejecting stroke, means operatively engageable with the 65 ejector operating means upon initial movement of the ram on its return stroke for moving the ejector operating means in the work ejecting direction to partially eject the work, and additional 70 means operatively connected with the ram and the ejector operating means and operated by con-

tinued movement of the ram on its return stroke to eject the work farther.

2. In a forging press including a frame, a reciprocable ram, means for driving the ram, a die carried by the ram, and an ejector for work formed by the die and carried by the ram; means for operating the ejector and comprising ejector operating means carried by the ram and movable concurrently therewith and relative thereto, and operative, when moved in one direction relative to the ram, to operate the ejector on its ejecting stroke, means on the frame operatively engageable with the ejector operating means when the ram moves on its return stroke for moving the ejector operating means initially in said direction, and means carried by the ram and operative for subsequently moving the ejector operating means additionally in said direction upon continued movement of the ram on its return stroke.

3. In a forging press including a frame, a reciprocable ram, a die carried by the ram, and an ejector for the die and carried by the ram, means for operating the ejector and comprising a member carried by the ram for movement relative to the ram and operative when it is moved relative to the ram in one direction to move the ejector on its ejecting stroke, a latch mechanism carried by the frame and normally operative to engage the member and constrain the member to movement relative to the ram in said one direction while the ram is moving part way on its return stroke and thereby to effect an ejecting operation of the ejector, and means operated by the ram, when the ram has moved on its return stroke beyond a predetermined position, to release said latch whereby the ejector is free from operation by said latch mechanism during the remainder of the return stroke beyond said position.

4. In a forging press having a frame, a reciprocable die-carrying ram, an ejector carried by the ram, mechanism for reciprocating the ram, and ejector operating mechanism carried by the ram and operated by the ram reciprocating mechanism for moving the ejector on its ejecting stroke during movement of the ram on its return stroke after the ram has completed an initial portion of its return stroke, and means on the frame and cooperating with the said ejector operating mechanism for actuating said ejector operating mechanism for moving the ejector initially on its ejecting stroke.

5. In a forging press of the type wherein a pitman-operated ram carries a forming die and also an ejecting means which is operable to move formed work outwardly of a cavity of the die, successively acting mechanisms, one of which has a part independent of the ram for acting on the ejecting means to cause it partially to eject work during an initial part of the return stroke of the ram, the other mechanism being operatively connected with the pitman for actuation thereby additionally to operate the ejector.

6. In a forging press including a frame, a reciprocable ram, a pitman for driving the ram, a die carried by the ram, and an ejector for work formed by the die carried by the ram, means for operating the ejector and comprising ejector operating means carried by the ram and movable concurrently therewith and relative thereto, and operative, when moved in one direction relative to the ram, to operate the ejector on its ejecting stroke, means on the frame operatively engageable with the ejector operating means when the ram moves on its return stroke for moving the

5 ejector operating means initially in said direction, and means operatively associating the ejector operating means and pitman for subsequently moving the ejector operating means by the pitman additionally in said direction upon additional movement of the ram on its return stroke.

7. In a forging press including a frame, a reciprocable ram, a die carried by the ram, and an ejector for the die and carried by the ram, mechanism for operating the ejector and comprising means connected to the ram for movement relative to the ram and operative when it is moved relative to the ram in one direction to move the ejector on its ejecting stroke, a mechanism carried by the frame and having an abutment positioned to engage said means when the ram is moved initially on its return stroke and thereby to effect movement of the said means relative to the ram in said direction, means carried by the ram and operative to move the abutment out of the path of movement of said first named means when the ram has moved a predetermined distance on its return stroke.

8. In a forging press of the type wherein a reciprocating ram carries a forming die and also an ejecting means which is operable to move formed work outwardly of a cavity of the die, successively acting mechanisms, one of which mechanisms has a part which acts on the ejecting means to cause it partially to eject work during an initial part of the return stroke of the ram, the other mechanism acting to operate the ejecting means more rapidly in the direction to eject work for a predetermined unit of return stroke movement of the ram than does the mechanism which acts during said initial part of the return stroke aforesaid.

9. In a forging press including a frame, a reciprocable ram, a pitman for reciprocating the ram, a die carried by the ram, and ejecting means carried by the ram for work formed by the die, an abutment carried by the frame and operative to engage a part of said ejecting means when the ram is moved initially on its return stroke so as initially to move the work outwardly of the die, said abutment and part being relatively movable in such a manner that one can pass the other during further movement of the ram on its return stroke, means operated by the pitman to effect further ejecting of work when the ram has

5 completed a further predetermined part of its movement on its return stroke, said pitman operated means being adapted and arranged to cause an overrunning movement of said part of the ejecting means relative to the abutment engaged thereby at an initial part of the operation of the pitman operated means whereby to separate the abutting surfaces, and means adapted and arranged then to effect said relative movement of the abutment and said part of the ejecting means 10 for enabling one to pass the other as aforesaid.

10. In a forging press including a frame, a reciprocable ram, a pitman for reciprocating the ram, a die carried by the ram, and an ejector carried by the ram for work formed by the die; mechanism for operating the ejector and comprising means carried by the ram for concurrent movement relative to and with the ram in one direction to move the ejector on its ejecting stroke, a movable abutment carried by the frame 15 and operative to engage a part of said means when the ram is moved initially on its return stroke thereby to effect movement of the said means relative to the ram in said direction, means operated by the pitman to effect more rapid movement of said first means additionally in said direction when the ram has completed a predetermined part of its movement on its return stroke, said pitman operated means and the movable abutment being in operating relationship to the first named means concurrently during part of said movement of the ram whereby the abutment and the part engaged thereby are separated by the difference in rapidity of the effected movements described, and means operated by the ram to cause the abutment to be moved out of the path of movement of said part which it engages after such separation.

11. In a forging press including a frame, a reciprocable ram, a pitman for reciprocating the ram, a die carried by the ram, and an ejector carried by the ram for ejecting work formed by the die; mechanism carried by the ram and operable to actuate the ejector on its ejecting stroke, and means on the pitman and operatively associated with the mechanism for operating said mechanism when the pitman is operated for moving the ram on the return stroke of the ram.

HENRY A. ZWIERLEIN. 50
